DESIGN FOR A WHEELED TOY

Ralph E. Stowell, Wellington, Tex.

Application May 24, 1945, Serial No. 119,697

Term of patent 14 years

(Cl. D34—15)

To all whom it may concern:

Be it known that I, Ralph E. Stowell, a citizen of the United States, residing at Wellington, in the county of Collingsworth and State of Texas, have invented a new, original, and ornamental Design for a Wheeled Toy, of which the following is a specification, reference being had to the accompanying drawing, forming part thereof.

Figure 1 is a perspective view of a wheeled toy showing my new design, and

Figure 2 is a front elevational view.

I claim:

The ornamental design for a wheeled toy, as shown.

RALPH E. STOWELL.
